(57) **CLAIM**

The ornamental design for wrap around cooler for wine boxes, as shown and described.

DESCRIPTION

FIG. 1 is an elevation view of the inside surface of a wrap around cooler for wine boxes showing my new design, the broken, vertical lines r indicating unclaimed fold lines;

FIG. 2 is a top, front, left side perspective view of the outside surface of the claim, applied to an unclaimed wine box;

FIG. 3 is a top, rear right side perspective view thereof; and,
FIG. 4 is an inside elevation view of the claim shown without fold lines.

FIGS. 2 and 3 show a wine box with phantom lines. The wine box is shown for purposes of showing the cooler in use and do not form any part of the claimed design. Further fold lines in FIG. 1 are phantom features and are not part of the design but merely an indicator or where the article would be folded.
